UNITED STATES PATENT OFFICE

171,191

TOOL DISPLAY RACK

Clifford A. Bowman, Michigan City, Ind., assignor
to Gardex, Inc., Michigan City, Ind., a corpo-
ration of Indiana

Application December 23, 1952, Serial No. 22,843

Term of patent 14 years

(Cl. D80—9)

To all whom it may concern:

Be it known that I, Clifford A. Bowman, a citizen of the United States, residing at Long Beach, Michigan City, in the county of La Porte, State of Indiana, have invented a new, original, and ornamental Design for a Tool Display Rack, of which the following is a specification, reference being had to the accompanying drawings forming part thereof.

Fig. 1 is a perspective view of a tool display rack showing my new design;

Fig. 2 is a top plan view; and

Fig. 3 is a side elevational view thereof.

I claim:

The ornamental design for a tool display rack, as shown.

CLIFFORD A. BOWMAN.
